UNITED STATES PATENT OFFICE.

JOEL G. CLEMMER, OF PHILADELPHIA, PENNSYLVANIA.

TALKING-MACHINE.

1,334,736.

Specification of Letters Patent. Patented Mar. 23, 1920.

Application filed October 10, 1917. Serial No. 195,697.

To all whom it may concern:

Be it known that I, JOEL G. CLEMMER, a citizen of the United States, residing at Philadelphia, in the State of Pennsylvania, have invented a certain new and useful Improvement in Talking-Machines, whereof the following is a specification, reference being had to the accompanying drawings.

My invention relates to sound recording and reproducing machines, including gramophones and graphophones; and particularly feed mechanism for sound boxes of such machines adjustable to automatically repeat their coöperation with a given sound record, 15 at the will of the operator.

As hereinafter described, my invention is specifically adapted for such machines arranged to coöperate with flat disk records, and having sound conducting tubular arms 20 or horns which move with the sound boxes, and are so constructed and arranged that repetition of the coöperation of the sound box with any given record is consequent upon such movement, to an adjustably determined extent.

In each of the embodiments of my invention chosen for illustration herein, the operation of the feed mechanism aforesaid is initiated by electrically actuated means.

30 I find it convenient to illustrate and describe my invention herein in connection with a graphophone of the type known commercially as "The New Edison Diamond Amberola," and also in connection with a 35 gramophone of the type known commercially as a "Victor Talking Machine." However, it is to be understood that I do not desire to limit myself to such specific embodiments of my invention, which includes the various novel features of construction and arrangement hereinafter more definitely specified.

It may be observed that although the two embodiments of my invention chosen for 45 illustration herein are specifically different in their details of construction; they each include means to variably predetermine the initial and terminal positions of the respective sound boxes with reference to given 50 sound records, in combination with a single rotary cam constructed and arranged to automatically lift the sound box from coöperative relation with the record when it

reaches a variably predetermined terminal position and to then return the sound box 55 to its initial position and again lower it into coöperative relation with the record; said cam having the capacity to shift said sound box, throughout the maximum range of its movement, by frictional engagement with a 60 cam plate carried with the sound box, but its effective capacity is adjustably variable in accordance with variations in the extent of different sound records.

In the drawings: Figure I is a plan view 65 of the Edison graphophone aforesaid, having a convenient embodiment of my invention in connection therewith.

Fig. II is a front view of the machine shown in Fig. I, but with portions of the 70 cabinet and the record driving motor omitted, to more clearly show the details of construction and arrangement of my invention.

Fig. III is a plan sectional view, taken on 75 the line III, III in Fig. II.

Fig. IV is a fragmentary elevation of the left hand end of the automatic feed mechanism shown in Fig. III.

Fig. V is a plan view of the Victor gramophone aforesaid having a convenient embodiment of my invention in connection therewith.

Fig. VI is a side elevation of said machine shown in Fig. V.

Fig. VII is a full size plan view of the 85 automatic feed mechanism indicated in Figs. V and VI.

Fig. VIII is a left hand side elevation of 90 said mechanism shown in Fig. VII.

Fig. IX is a sectional view of said mechanism, taken on the line IX in Fig. VII.

Fig. X is a fragmentary sectional view, taken on the line X in Fig. VII.

Fig. XI is a fragmentary elevation of the 95 left hand side of a sound box such as shown in Fig. I, but embodying a modified form of my invention.

Fig. XII is a front elevation of the mechanism shown in Fig. XI.

Fig. XIII is a fragmentary plan view of the feed cam and the mechanism, shown at the right hand side of Figs. I, II and III, whereby said cam is actuated.

Referring to the form of my invention 105 shown in Figs. I to IV inclusive; 1 is a cas-

ing inclosing a graphophone including the record turn table 2 arranged to be turned by the motor 3, which is only indicated in dotted lines in Fig. I, but is mounted upon the under side of the graphophone table plate 4 which is rigidly secured in said casing 1. The sound box 5, which is carried by the tubular tone arm 6, includes a vibratory diaphragm and carries the stylus 7, indicated in Fig. II, arranged to traverse a groove in a record 9 on said turn table and automatically shift said box toward the axis of said table. The amplifying horn 10 is rigidly connected with said tone arm 6 and with the vertical shaft 12 which forms a pivot upon which said box 5, arm 6 and horn 10 oscillate together.

As it is the purpose of my invention to shift said sound box from its terminal position upon any record to its proper initial position with respect to such record, it is important to note that there is considerable variation in the radial position of the initial and terminal portions of sound record grooves in records of the same nominal size, and, therefore, I provide stop mechanism which is adjustably variable to predetermine the initial and terminal positions of the sound box 5 with reference to any given record.

The adjustable initial stop lever 13, indicated in Fig. I, is arranged to limit the initial position of said box 5 in coöperation with said record 9 at the outer limit of its movement with respect to the axis of said table 2, by the curved portion 14 thereof provided with the padded inner face 15 to encounter the vertically extending portion of said horn 10 as indicated in Fig. I. Said initial stop lever 13 is fulcrumed at 17 in connection with said table plate 4 and is flexible so that its free end may be vertically shifted to and from engagement with the toothed rack 18 which is rigidly connected with said casing 1. Of course, said stop lever may be thus manually adjusted to any position corresponding with the greatest radial extent of the record groove in said record 9; or it may be adjusted in correspondence with the radial position of any other point in said record groove at which it is desired to initiate or resume the coöperation of said stylus 7 with said record groove.

As said sound box 5 is carried across the record 9 in coöperative relation therewith and toward the axis of said table 2, said horn 10 is swung in the direction of the arrows indicated in Figs. I and III; its terminal position being indicated in dotted lines in Fig. III, corresponding with the terminal position of said sound box 5 with reference to said record 9; and the adjustable terminal stop lever 20 is arranged to variably limit the terminal position of

said box 5 by variation in the radial extent of the stop arm 21 of said lever 20 which, as indicated in Fig. II, is upturned to encounter the edge of said sound box 5. Said stop arm 21 has the gear rack 22 mounted to slide transversely in the hood 23 on said lever 20 and is adjusted by rotation of the gear 25 by the knob 26, both of which are fixed on the shaft 27 journaled in said lever 20. Said lever has the fulcrum shaft 28, indicated in dotted lines in Fig. II, rigidly connected therewith but mounted to turn in the base bearing 29 which is fixed on said casing 1 by the screws 30 indicated in Fig. I. Said stop lever 20 is normally held in operative position by its spring 31 which extends from said base 29 in engagement with a notch 32 in said lever as indicated in Fig. II. However, when it is desired to render said lever 20 inoperative, it may be manually turned in the direction of the arrow marked thereon in Fig. I; such movement automatically disengaging said spring 31 from said notch 32 and permitting it to engage the notch 34 to hold said lever in inoperative position until manually returned.

Although it is not essential; I prefer to provide said stop arm 21 of said lever 20 with the pointed index 36, shown in Fig. I, for convenient registration with the particular point in the record groove at which it is desired to terminate the coöperative relation of the stylus and record and shift the sound box to repeat the operation. Therefore, it is to be understood that the construction and arrangement of said terminal stop mechanism is such that it may be precisely adjusted in accordance with the radial position of any selected terminal point of the sound groove in any record capable of coöperation with the mechanism above contemplated; so that when said sound box and horn reach such terminal point, their coöperation with said record shall be interrupted while they are shifted to another predetermined point, at which their coöperation with said record may be resumed, and without interruption of the operation of the ordinary mechanism of the talking machine, including said motor 3.

The automatic feed mechanism which is arranged to raise said horn 10, tone arm 6 and the box 5 from their terminal position, shift said box away from the axis of said table 2 and lower them to their initial position, includes the cam 42 shown in Figs. II, III and IV, which is rigidly connected with the cam shaft 43, mounted to revolve on a horizontal axis and axially reciprocates in the frame 45. During its operation, said cam 42 is arranged to frictionally engage the under surface of the cam plate 48, which is rigidly connected with said shaft 12 in the position shown in Figs. II and III, 130

However, said cam 42 normally remains stationary during the coöperation of the sound box with the record; that is to say, while the sound box is traversing the record from 5 its initial to its terminal position with respect thereto; said cam plate 48 merely slides upon the flat portion of said cam 42 (best shown in Fig. IV), then presented, horizontally, at the top thereof.

10 In the form of my invention shown in Figs. II, III and IV; said cam shaft 43 is part of driving mechanism which may be automatically connected and disconnected with respect to said motor 3, as hereinafter 15 described. When operatively connected, said cam is turned in the direction of the arrow marked thereon in Fig. IV, but is prevented from turning, when disconnected, by the frame member 50 which engages the 20 recess 51 in the disk 52 which is rigidly connected with said shaft 43, which shaft is arranged to axially reciprocate in said frame 45. Said shaft carries, rigidly connected therewith, the clutch gear 54 which is bevelled and arranged to mesh with the driving 25 gear 55 on the counter shaft 56, which is journaled in the bearing 57 (rigidly connected with said casing 1), and has at its opposite end the bevel gear 59 which is continually engaged with the bevel gear 60 on 30 the shaft 61 of said motor 3 so that said counter shaft 56 is continuously revolved during the operation of said motor. However, said cam shaft 43 is intermittently connected 35 with that driving mechanism by means of the clutch lever 62 which is fulcrumed at 63 on said frame 45 and has its free end engaged in the grooved collar 65 which is rigidly connected with said shaft. 40 Said clutch lever is shifted alternately in either direction, to axially reciprocate said shaft 43 and thus connect and disconnect said clutch gear 54 with respect to said driving gear 55, by means including the slide bar 45 66 which is mounted to reciprocate in said frame 45 and has the tappet block 67 rigidly connected with it. Said tappet and its slide bar are operatively connected with said clutch lever by the clutch spring 69 which 50 is attached to said tappet block 67 at one end and to said lever 62 at the other end, the frame 45 being notched beneath said lever 62, as indicated in dotted lines in Fig. III, to permit said lever to swing to the right 55 without contact between said frame 45 and said spring 69 which, when free to collapse, shifts said slide bar 66 and said tappet block 67 toward said clutch lever 62 and also shifts the latter to engage the gear 54 with the gear 60 55, by axial movement of said shaft 43, toward the right. Such movement is effected solely by the tension of said spring 69, because it is then effective to move the tappet block 67 and lever 62 closer together and, 65 because said lever is held stationary at the axis of its fulcrum 63, such tension is translated into movement of the opposite end of said lever toward the right in Fig. III; but in the position of the parts shown in Fig. III, said spring 69 is stretched so as to stress 70 said clutch lever 62 toward the left to disconnect said clutch gear 54 from said driving gear 55 when said disk 52 is turned far enough to bring its recessed portion 51 into registry with said frame projection 50. 75 Said clutch spring 69 is held in that position by the detent 70 which is fulcrumed at 71 and provided with the detent spring 72 so that it snaps into engagement with and normally detains said tappet 67 in the position 80 shown in Fig. III. As above stated; said spring 69 operates to shift the clutch gear 54 in both directions, solely by tension of said spring and in both instances effects a change 85 in the angular relation of the lever 62 with reference to the plane which is common to the axes of said shaft 43 and said slide bar 66. When said spring has its left hand end held stationary, by engagement of the tappet block 67 with the detent 70, as shown in Fig. 90 III, said spring tends to increase the angle between the left hand edge of said lever 62 and said plane, thus tending to shift the shaft 43 and its appurtenances to the left. However, when the left hand end of said 95 spring 69 is free to move, by release of said detent 70 from said tappet block 67, as indicated in Fig. XIII, said spring tends to decrease the angle aforesaid by drawing said tappet block 67 and said lever 62 closer together and, because said lever 62 is anchored to the frame 45, at its fulcrum 63, the tension 100 of said spring effects movement of said shaft 43 to the right. Said detent 70 forms the armature of the electromagnet 73 which is capable of releasing it from said tappet 67, 105 against the stress of said detent spring 72, when energized by closure of the circuit connecting said magnet with a source 74 of electric energy and including the conductors 75 and 76. The means arranged to make and break said circuit, by movement of said box 5, include the electric contact terminal 78 carried by said box, and the electric contact terminal 79 carried by said arm 21 of the 110 terminal stop lever 20.

In the drawings; the initial stop lever 13 is supposed to be adjusted in correspondence with the initial convolution 80 of the groove in said record 9; and the terminal stop lever 20 is supposed to be adjusted in correspondence with the terminal convolution 81 of said groove; so that when said stylus 7 reaches said terminal convolution 81, the electric circuit is completed by contact of the terminal 78 on said box 5 with the terminal 79; so that said detent 70 is then drawn out of engagement with said tappet 67 by said electromagnet 73; thus permitting said clutch spring 69 to snap said shaft 115 120 125 130

43 toward the right in the drawings to engage the clutch gear 54 with said driving gear 55. The continued revolution of said driving gear 55 then turns said cam shaft 5 43, and the cam 42 carried thereon, in the direction of the arrow shown in Fig. IV with the effect that said horn 10, arm 6 and sound box 5 are uplifted from coöperative relation with said record 9 and then turned, 10 by frictional engagement of said cam 42 with said cam plate 48, on said shaft 12, until said tone arm 6 encounters the padded inner face 15 of the initial stop lever 13 as indicated in Fig. I. Further turning movement of said cam 42 merely lowers said horn, arm and box 5 to their initial position in coöperative relation with said record. During that operation, said clutch spring 69 is reset to the position shown in Fig. III 15 (i. e., with the tappet block 67 shifted to the left and there engaged by said detent 70) by means of the crown cam 83, shown in Figs. II and IV, which turns with said shaft 43 and is conveniently mounted upon said 20 clutch gear 54 so as to thrust said slide bar 60 to the left, in Figs. II and III. Fig. IV shows the parts nearing the completion of the operation of the box feed mechanism; and as above noted, when the recess 51 registers with the projecting frame member 50 (which, until then, holds the clutch gear 54 in engagement with the driving gear 55), said clutch spring 69 snaps said shaft 43 to 25 the left in the drawings, thus disengaging said clutch and locking the feed mechanism against accidental rotation from its inoperative position by engagement of said disk 52 with said projection 50. Whereupon, the coöperation of said stylus 5 and record 9 is 30 resumed and repeated; only a few seconds intermission being required for the automatic return of the sound box 5 from its terminal to its initial position as above contemplated.

45 Referring to the form of my invention shown in Figs. V to X inclusive; 85 is a casing inclosing a gramophone including the record turn table 86 arranged to be turned by the motor 87 which is only indicated in 50 dotted lines in Fig. VI but is mounted upon the underside of the casing top 88 which is detachably rigidly secured on said casing 85. The sound box 89, which is carried by the tubular tone arm 90, includes a vibratory 55 diaphragm and carries the stylus 91, indicated in Fig. VI, arranged to traverse a groove in a record 93, on said turn table 86, and automatically shift said box toward the axis of said table. The amplifying horn 60 94 is rigidly connected with said casing 85 but is pivotally connected with said tone arm 90 at 95.

The collar 96, which is detachably secured upon said horn 94 by the set screw 97, carries the adjustable initial stop lever 98,

which is arranged to be manually secured in adjusted position by the set screw 99 shown in Figs. V and VII. Said lever 98 rests upon the flange 100 of said collar 96, which is conveniently graduated as indicated at 102 in Fig. VII so as to be traversed by the index lug 103 on said lever 98; whereby the position of said lever may be accurately determined so as to limit the initial position of said box 89 in coöperation with said record 93 at the outer limit of its movement with respect to the axis of said table 82.

As said sound box 89 is carried across said record 93 in coöperative relation therewith and toward the axis of said table 86, 80 said tone arm 90 is swung in the direction of the arrow indicated in Fig. V; its terminal position being indicated by the dash lines in that figure corresponding with the terminal position of said sound box 89 with 85 reference to said record 93, and the adjustable terminal stop lever 106 is arranged to variably limit the terminal position of said box 89 by adjustment of said lever 106 circumferentially with respect to its fulcrum 90 upon the screw 107 which has the milled head 108 whereby it may be manually turned to clamp said lever 106 in adjusted position. As hereinafter described, the free end of 95 said lever 106 is an electric contact terminal of a circuit controlling the operation of the sound box feed mechanism shown in Figs. V to X inclusive.

As indicated in Fig. VI; said motor 87 has the shaft 110 provided with the bevel gear 111 continually engaging the bevel gear 112 on the counter shaft 113 which carries the driving gear 114, so that the latter is continuously revolved during the operation of said gramophone. The automatic feed mechanism for said sound box 89 includes the clutch gear 115 is alternately operatively connected and disconnected with respect to said driving gear 114, as follows:

As best shown in Figs. VII and VIII; said clutch gear 115 is carried by the sleeve 117, which is journaled, for rotation and axial reciprocation, upon the stationary stud shaft 118 (which is rigidly connected 115 with said collar 96) and is shifted to and from engagement with said driving gear 114 by the clutch lever 120 which is fulcrumed at 121 upon the frame plate 122. Said clutch lever 120, has its free end extending between said clutch gear 115 and the flange 123 on said sleeve 117, and is provided with the clutch spring 125 which is constructed and arranged to snap said lever 120 and said clutch gear 115 both to 120 and from their operative position. As indicated in Fig. VII said spring 125 is under longitudinal tension and transverse flexion between said levers 120 and 126. Said spring 125 is set to snap said lever 120. 125

to the inoperative position shown in Fig. VII (and to retain it in that position until released), by the lever 126 which is fulcrumed on the screw 127 rigidly connected 5 with said plate 122. Said lever 126 has its tappet arm 129 engaged by the detent lever 130 (best shown in Fig. VIII) which is pivoted on the screw 131 which is in rigid relation with said plate 122. Said detent 10 130 is pressed into the position shown in Fig. VIII by the spring 132 which is also rigidly connected, at one end, with said plate 122. Said detent 130 may be manually released by movement in the direction of the arrow marked on the right hand end thereof in Fig. VIII; such movement being in opposition to the pressure of said spring 132. However, I provide electrically controlled means for effecting such release 15 and thus initiating the operation of the automatic box feed mechanism, including the electromagnet 134 having the armature 135 pivoted at 136, in connection with said base plate 122, and having its free end resting 20 upon the right hand end of said detent lever 130 as shown in Figs. VII and VIII. It is to be understood that when said electro-magnet 134 is energized, said armature 135 is instantaneously drawn down to release said 25 spring lever 126 and permit the spring 125 to collapse and shift said clutch lever 120 in the direction of the arrow marked thereon in Fig. VII (by the longitudinal collapse and horizontal flexure of said spring 125, which 30 tends to straighten itself; supplemented by the consequent momentum of said lever 126) to engage said clutch gear 115 with said driving gear 114. Said electromagnet is thus energized by closure of the electric circuit including the conductors 138 and 139, indicated in Fig. V, which are respectively connected with said terminal stop lever 106 and with the metallic parts in electrical connection with said tone arm 90. As shown 35 in Fig. V; said conductor 139 includes the coil of said electro-magnet 134 and has its end clamped upon the base plate 122 by the bracket carrying the fulcrum of the lever 130. Said base plate is in electric 40 circuit with the tone arm 90 by the metallic parts shown engaging each other in Figs. V and VI. As the sound box 89 is normally electrically insulated from said tone arm 90 by the soft rubber flange 141 which is part 45 of the ordinary Victor machine structure; I prefer to electrically connect said box 89 with said tone arm, and thus with said conductor 139, by means of the conductor 142 indicated in dotted lines in Fig. V, bridging 50 said insulating flange 141; so that said circuit 138 and 139 including said electromagnet 134 and the generator 143, is closed when said sound box 89 touches the terminal end of said adjustable terminal lever 55 106. It is to be understood that said lever

is so adjusted that said circuit is thus closed when said stylus 91 reaches the terminal convolution 145 on said record 93.

As shown in Fig. X, said flange 123 on said clutch sleeve 117 has the recess 147 to receive the stud 148 which is rigidly connected with said base plate 122; so that when said clutch gear 115 is in the inoperative position shown in Fig. VII it is thus prevented from accidentally turning. 70 However, when said clutch gear is thrust into its operative position, as above described, said flange 123 is shifted, with the clutch sleeve 117, to the right of its position shown in Fig. VII, far enough to clear 75 said stud 148, and, as said sleeve is immediately turned by the engagement of said gears 114 and 115, said stud 148 prevents the accidental disengagement of said gears until the gear 115 has made a complete revolution, again presenting its recess 147 in registry with said stud 148. During that revolution of the sleeve 117 the spring 125 is reset to the position shown in Fig. VII 80 by the crown cam 150, which is also rigidly connected with said sleeve 117, and then encounters the stud 151 which is rigidly connected with said spring lever 126. It is to be understood that during said revolution 85 said lever 126 is gradually pressed in the opposite direction to that indicated by the arrow thereon in Fig. VII, until its end 129 again snaps into engagement with the detent lever 130, in the position shown in 90 Figs. VII and VIII. Therefore, when said 100 single revolution of the sleeve 117 is completed, said spring 125 has been so set, in extended position, that when said recess 147 in the flange 123 is presented in registry 105 with the stud 148, as shown in Fig. X, said 110 sleeve 117 is instantly snapped toward the left in Fig. VII to disengage the clutch gear 115 from the driving gear 114.

During that single revolution of the sleeve 117 of the box feed mechanism, said 110 box 89 is raised from the record 93, and, with its tone arm 90, returned to its initial position, in the direction opposite to the arrow shown in Fig. V, by means of the single cam 152, best shown in Fig. IX, 115 which registers with the arcual arm 153 on the lever 154, shown in Figs. V and VI, which is fulcrumed on the stud 155 rigidly connected with said tone arm 90. When said cam 152 reaches its normal position 120 shown in Fig. IX, said lever 139 has been returned to its normal position shown in Figs. V and VI, by the weight of the sound box 89 which gravitates to operative position with respect to the sound record 89 as 125 the arcual end 133 of said lever 139 is lowered by said cam 152; the automatic feeding movement described having been effected in a few seconds by the single revolution 130 of said sleeve 117.

In both of the embodiments of my invention above described, the closure of the electric circuit which initiates the operation of the box feed mechanism is effected by contact of two electric terminals, one of which is carried by the sound box and the other of which is stationary except when manually adjusted as described. However, my invention may be embodied in a sound producing machine which does not require any manual adjustment of the electric terminals at which closure of the circuit is effected. For instance, in the form of my invention shown in Figs. XI and XII, which includes a graphophone sound box 156, (which it is to be understood is associated with the other essential elements of a graphophone of the general character shown in Figs. I to IV inclusive;) the closure of the electric circuit is effected by contact of the terminals 157 and 158, both of which are carried by, or in connection with, said sound box 156. As indicated in Fig. XII, said terminal 157 is a wire loop, pendent from said sound box 156 but having the right hand portion thereof insulated as indicated by the black portion 159 thereof. Said terminal 158, which extends freely through said loop terminal 157, is carried by the stylus lever 160 which is mechanically connected with said sound box 156, as indicated in Fig. XI, but is electrically insulated therefrom by the insulation 161. Therefore, it is to be understood that the electric conductors 162 and 163, shown in Fig. XI, are opposite sides of a circuit including a source of electric energy and an electromagnet, such as above described, constructed and arranged to initiate the operation of an automatic feed mechanism for sound boxes. When in operative relation with the sound record, said sound box 156 is moved in the direction of the arrow marked thereon in Fig. XII and, during such movement, said terminal 158 is free from the terminal 157 and prevented from making an electric connection by the insulation 159. However, when said box reaches the end of the record groove, said terminal 158 is permitted to contact with said terminal 157 by relative lateral movement, to thus automatically initiate the operation of the feed mechanism to return said box 156 to its initial position.

Although each of the embodiments of my invention above described, includes electrically controlled means for initiating the operation of the automatic feed mechanism for the sound box; it may be observed that my invention includes certain features of mechanical construction and arrangement to which the specific construction and arrangement of the electric controlling means is not essential.

Therefore, I do not desire to limit myself to the precise details of construction and ar-

angement of my invention herein set forth, as it is obvious that various modifications may be made therein without departing from the essential features thereof as defined in the appended claims.

I claim:

1. In a talking machine; the combination with a motor arranged to turn a sound record; of a sound box; an initial stop lever, limiting the initial position of said box; a terminal stop lever, limiting the terminal position of said box; means arranged to raise said box from said terminal position and return it to its initial position, including a frame, a feed cam carried by a horizontal shaft arranged to axially reciprocate in said frame, and driving mechanism for said cam, operatively connected with said motor, and including a clutch gear on said shaft; means arranged to shift said clutch gear and its shaft to and from position to revolve said cam, including a clutch lever on said frame, a slide bar on said frame, carrying a tappet, a clutch spring connecting said clutch lever and slide, a clutch cam on said gear, arranged to shift said slide and set said clutch spring to release said clutch, a disk on said shaft arranged to bear longitudinally upon said frame and prevent axial movement of said shaft during the operation of said feed cam, and permit axial movement of said shaft when said feed cam is in inoperative position, and a pivoted magnet armature detent arranged to catch said tappet when the latter is set by said clutch cam; a spring for said detent; an electro-magnet capable of releasing said armature detent from said tappet, against said detent spring; a circuit connecting said magnet with a source of electric energy; and means arranged to make and break said circuit, including an electric contact terminal carried by said sound box, and an electric contact terminal carried by said terminal stop lever.

2. In a talking machine; the combination with a motor arranged to turn a sound record; of a sound box; an initial stop lever, limiting the initial position of said box; a terminal stop lever, limiting the terminal position of said box; means arranged to raise said box from said terminal position and return it to its initial position, including a frame, a feed cam carried by a horizontal shaft, and driving mechanism for said cam, operatively connected with said motor, and including a clutch on said shaft; means arranged to shift said clutch to and from position to revolve said cam, including a clutch lever on said frame, a slide on said frame, carrying a tappet, a clutch spring connecting said clutch lever and slide, a clutch cam arranged to turn with said gear, to shift said slide and set said clutch spring to release said clutch, a disk on said shaft arranged to bear longitudinally upon said frame, and

- prevent axial movement of said shaft during the operation of said feed cam, and permit axial movement of said shaft when said feed cam is in inoperative position, and a 5 magnet armature detent arranged to catch said tappet when the latter is set by said slide cam; a spring for said detent; an electro-magnet capable of releasing said armature detent from said tappet, against said 10 detent spring; a circuit connecting said magnet with a source of electric energy; and means arranged to make and break said circuit, including an electric contact terminal, carried by said sound box, and an electric contact terminal, carried by said terminal stop.
3. In a talking machine; the combination with a motor arranged to turn a sound record; of a sound box; a terminal stop, limiting the terminal position of said box; means arranged to raise said box from said terminal position and return it to its initial position, including a frame, a feed cam carried by a horizontal shaft, and driving mechanism for said cam, operatively connected with said motor, and including a clutch on said shaft; means arranged to shift said clutch to and from position to revolve said cam, including a clutch lever on said frame, 20 a slide on said frame, carrying a tappet, a clutch spring connecting said clutch lever and slide, a clutch cam arranged to turn with said gear, to shift said slide and set said clutch spring to release said clutch, a 25 disk on said shaft, having means arranged to bear longitudinally upon said frame and prevent axial movement of said shaft during the operation of said feed cam, and permit axial movement of said shaft when said 30 feed cam is in inoperative position, and a magnet armature detent arranged to catch said tappet, when the latter is set by said slide cam; a spring for said detent; an electro-magnet capable of releasing said armature detent from said tappet, against said 35 detent spring; a circuit connecting said magnet with a source of electric energy; and means arranged to make and break said circuit, including an electric contact terminal, 40 carried by said sound box, and an electric contact terminal carried by said terminal stop.
4. In a talking machine; the combination with a motor arranged to turn a sound record; of a sound box; a terminal stop, limiting the terminal position of said box; means arranged to raise said box from said terminal position and return it to its initial position, including a frame, a feed cam carried by a shaft, and driving mechanism for said cam, operatively connected with said motor, and including a clutch on said shaft; means arranged to shift said clutch to and from position to revolve said cam, including a clutch lever on said frame, a tappet, 45 a clutch spring connecting said clutch lever and tappet, a clutch cam arranged to turn with said gear, to shift said tappet and set said clutch, to shift said tappet and set said clutch spring to release said clutch, a disk on said shaft arranged to bear longitudinally upon said frame and prevent axial movement of said shaft during the operation of said feed cam, and permit axial movement of said shaft when said feed cam is in inoperative position, and a magnet armature detent arranged to catch said tappet, when the latter is set by said cam; an electro-magnet capable of releasing said armature detent from said tappet; a circuit 50 connecting said magnet with a source of electric energy; and means arranged to make and break said circuit, including an electric contact terminal, movable with said sound box, and another electric contact terminal co-operative therewith.
5. In a talking machine; the combination with a motor arranged to turn a sound record; of a sound box; means arranged to raise said box from its terminal position and return it to its initial position, including a frame, a feed cam carried by a shaft, and driving mechanism for said cam, and including a clutch on said shaft; means arranged to shift said clutch to and from position to revolve said cam, including a clutch lever on said frame, a tappet, a clutch spring connecting said clutch lever and tappet, a clutch cam arranged to turn with said clutch, to shift said tappet and set said clutch spring to release said clutch, a disk on said shaft arranged to bear longitudinally upon said frame and prevent axial movement of said shaft during the operation of said feed cam, and permit axial movement of said shaft when said feed cam is in inoperative position, and a magnet armature detent arranged to catch said tappet, when the latter is set by said cam; an electro-magnet capable of releasing said armature detent from said tappet; a circuit connecting said magnet with a source of electric energy; and means arranged to make and break said circuit, including an electric contact terminal, movable with said sound box, and another electric contact terminal co-operative therewith.
6. In a talking machine; the combination with a motor arranged to turn a sound record; of a sound box; an initial stop lever limiting the initial position of said box; means arranged to raise said box from said record and lower it to operative relation with said record, including a frame, a feed cam carried by a horizontal shaft, arranged to axially reciprocate in said frame, and driving mechanism for said cam, operatively connected with said motor, and including a clutch gear on said shaft; means arranged to shift said clutch to and from position to revolve said cam, including a clutch lever 120

on said frame, a slide on said frame, carrying a tappet, a clutch spring connecting said clutch lever and slide, a clutch cam on said gear, arranged to shift said slide 5 and set said clutch spring to release said clutch, a disk on said shaft arranged to bear longitudinally upon said frame and prevent axial movement of said shaft during the operation of said feed cam, and permit axial 10 movement of said shaft when said feed cam is in inoperative position, and a pivoted detent arranged to catch said tappet when the latter is set by said clutch cam; and means, operated by movement of said box, 15 arranged to release said detent when said stylus reaches a certain point in said groove.

7. In a talking machine; the combination with a motor arranged to turn a sound record; of a sound box; means arranged to raise 20 said box from said record and lower it to operative relation with said record, including a frame, a feed cam carried by a horizontal shaft, arranged to axially reciprocate in said frame, and driving mechanism for said cam, 25 operatively connected with said motor, and including a clutch gear on said shaft; means arranged to shift said clutch to and from position to revolve said cam, including a clutch lever on said frame, a slide on said 30 frame, carrying a tappet, a clutch spring connecting said clutch lever and slide, a clutch cam on said gear, arranged to shift said slide and set said clutch spring to release said clutch, a disk on said shaft arranged 35 to bear longitudinally upon said frame and prevent axial movement of said shaft during the operation of said feed cam, and permit axial movement of said shaft when said feed cam is in inoperative position, and a pivoted detent arranged to catch said tappet when the latter is set by said clutch cam; and means, operated by movement of said box, arranged to release said detent when said stylus reaches a certain 40 point in said groove.

8. In a talking machine; the combination with a motor arranged to turn a sound record; of a sound box; means arranged to raise said box from said record and lower it 50 to operative relation with said record, including a frame, a feed cam carried by a shaft, and driving mechanism for said cam, operatively connected with said motor, and including a clutch on said shaft; means arranged 55 to shift said clutch to and from position to revolve said cam, including a clutch lever on said frame, a tappet, a clutch spring connecting said clutch lever and tappet, a clutch cam arranged to turn with said clutch, to shift said tappet and set said clutch spring to release said clutch, and a 60 detent arranged to catch said tappet when the latter is set by said clutch cam; and means, operated by movement of said box, arranged to release said detent when said stylus reaches a certain point in said 65 groove.

9. In a talking machine; the combination

tion of said feed cam, and permit axial 65 movement of said shaft when said feed cam is in inoperative position, and a detent arranged to catch said tappet when the latter is set by said clutch cam; and means, operated by movement of said box, arranged to 70 release said detent when said stylus reaches a certain point in said groove.

9. In a talking machine; the combination with a motor arranged to turn a sound record; of a sound box; means arranged to raise 75 said box from said record and lower it to operative relation with said record, including a frame, a feed cam carried by a shaft, and driving mechanism for said cam, operatively connected with said motor, and including a clutch on said shaft; means arranged to shift said clutch to and from position to revolve said cam, including a clutch lever on said frame, a tappet, a clutch spring connecting said clutch lever and tappet, a 80 clutch cam arranged to turn with said clutch, to shift said tappet and set said clutch spring to release said clutch, a disk on said shaft arranged to bear longitudinally upon said 85 frame and prevent axial movement of said shaft during the operation of said feed cam, and permit axial movement of said shaft when said feed cam is in inoperative position, and a detent arranged to catch said tappet when the latter is set by said clutch cam; and means, operated by movement of said box, arranged to release said detent when said stylus reaches a certain point in said 90 groove.

10. In a talking machine; the combination with a motor arranged to turn a sound record; of a sound box; means arranged to raise said box from said record and lower it to operative relation with said record, including a frame, a feed cam carried by a 100 shaft, and driving mechanism for said cam, operatively connected with said motor, and including a clutch on said shaft; means arranged to shift said clutch to and from position to revolve said cam, including a clutch lever on said frame, a tappet, a clutch spring connecting said clutch lever and tappet, a clutch cam arranged to turn with said clutch, to shift said tappet and set said clutch spring to release said clutch, and a 105 detent arranged to catch said tappet when the latter is set by said clutch cam; and means, operated by movement of said box, arranged to release said detent when said stylus reaches a certain point in said 110 groove.

11. In a talking machine; the combination with a motor arranged to turn a sound record; of a sound box; means arranged to raise said box from said record and lower it to operative relation with said record, including a frame, a feed cam carried by a shaft, arranged to axially reciprocate in 115

said frame and driving mechanism for said cam, operatively connected with said motor, and including a clutch gear on said shaft; means arranged to shift said clutch 5 to and from position to revolve said cam, including a clutch lever on said frame, a tappet, a clutch spring connecting said clutch lever and tappet, a clutch cam arranged to turn with said clutch, to shift 10 said tappet and set said clutch spring to release said clutch, and a detent arranged to catch said tappet when the latter is set by said clutch cam; and means, operated by movement of said box arranged to release 15 said detent when said stylus reaches a certain point in said groove.

12. In automatic feed mechanism for talking machine sound boxes; the combination with a rotary support for a sound record; of 20 a motor arranged to turn said support; a sound box including a stylus constructed and arranged to traverse a groove in a record on said support; and feed mechanism arranged to remove said box from operative 25 relation with said record, positively move it to another region of said record, and replace it in operative relation with said record, including a rotary clutch arranged to connect and disconnect said feed mechanism and 30 motor, without interruption of the operation of said motor, and electrically controlled means arranged to operate said clutch, including an electric contact movable with said box and another electric contact terminal 35 co-operative therewith.

13. In automatic feed mechanism for talking machine sound boxes; the combination with a rotary support for a sound record; of a motor; a sound box including a stylus 40 constructed and arranged to traverse a groove in a record on said support; and feed mechanism arranged to remove said box from operative relation with said record, positively move it to another region of said 45 record, and replace it in operative relation with said record, including a rotary clutch arranged to connect and disconnect said feed mechanism and motor without interruption 50 of the operation of said motor, and electrically controlled means arranged to operate said clutch.

14. In automatic feed mechanism for talking machine sound boxes; the combination with a rotary support for a sound record; of 55 a motor arranged to turn said support; a sound box including a stylus constructed and arranged to traverse a groove in a record on said support; and feed mechanism arranged to remove said box from operative relation 60 with said record, positively move it to another region of said record, and replace it in operative relation with said record, including a rotary clutch arranged to connect and disconnect said feed mechanism and

motor without interruption of the operation 65 of said motor, and electrically controlled spring means arranged to operate said clutch.

15. In automatic feed mechanism for talking machine sound boxes; the combination 70 with a rotary support for a sound record; of a motor; a sound box including a stylus constructed and arranged to traverse a groove in a record on said support; and feed mechanism arranged to remove said box 75 from operative relation with said record, positively move it to another region of said record, and replace it in operative relation with said record, including a rotary clutch arranged to connect and disconnect said 80 feed mechanism and motor without interruption of the operation of said motor, and electrically controlled spring means arranged to operate said clutch.

16. In automatic feed mechanism for talking machine sound boxes; the combination 85 with a rotary support for a sound record; of a motor; a sound box including a stylus constructed and arranged to traverse a groove in a record on said support; and feed 90 mechanism arranged to remove said box from operative relation with said record, positively move it to another region of said record, and replace it in operative relation with said record, including a rotary clutch 95 arranged to connect and disconnect said feed mechanism and motor, and electrically controlled spring means arranged to operate said clutch.

17. In automatic feed mechanism for a 100 sound producing machine; the combination with a rotary support for a sound record; of a motor; a sound box including a stylus constructed and arranged to traverse a groove in a record on said support; and feed 105 mechanism arranged to remove said box from operative relation with said record, positively move it to another region of said record, and replace it in operative relation with said record, including a rotary clutch 110 arranged to connect and disconnect said feed mechanism and motor, and electrically controlled means arranged to operate said clutch.

18. In automatic feed mechanism for a 115 sound producing machine; the combination with a rotary support for a sound record; of a motor; a sound box including a stylus constructed and arranged to traverse a groove in a record on said support; and feed 120 mechanism arranged to remove said box from operative relation with said record, positively move it to another region of said record, and replace it in operative relation with said record, including a rotary clutch 125 arranged to connect and disconnect said feed mechanism and motor, and electrically controlled means arranged to operate said

clutch, including a single spring arranged to snap said clutch alternately in opposite directions.

19. In automatic feed mechanism for a sound producing machine; the combination with a rotary support for a sound record; of a motor; a sound box including a stylus constructed and arranged to traverse a groove in a record on said support; and means arranged to remove said box from operative relation with said record, shift it to another region of said record, and replace it in operative relation with said record, including an axially reciprocatory shaft carrying, rigidly mounted thereon, a clutch arranged to connect and disconnect said feed mechanism and motor, a clutch spring arranged to snap said clutch shaft alternately in opposite directions; and means carried by said shaft, arranged to set said spring.
20. In a sound reproducing machine; the

combination with a motor arranged to turn a sound record; of a sound box; feed mechanism for said sound box, including an axially reciprocatory shaft carrying, rigidly mounted thereon, a rotary clutch arranged to connect and disconnect said feed mechanism and motor, a clutch spring arranged to snap said clutch shaft alternately in opposite directions; means carried by said shaft, arranged to set said spring; and electrically operative means arranged to release said spring, by movement of said sound box to a predetermined position.

In testimony whereof, I have hereunto signed my name at Philadelphia, Pennsylvania, this twenty-ninth (29) day of September, 1917.

JOEL G. CLEMMER.

Witnesses.
